FIG. 5

FIG. 1 is a front elevational view of a motion picture film editor or similar articles, showing my design;

FIG. 2 is a top plan view thereof;

FIG. 3 is a side elevational view thereof, the opposite side being substantially a mirror image thereof;

FIG. 4 is a rear elevational view thereof on a reduced scale; and

FIG. 5 is a fragmentary front perspective view of the central portion thereof on an enlarged scale.

I claim:

The ornamental design for a motion picture film editor or similar article, substantially as shown.
